BRAKE CYLINDER HONE

Thomas E. Brooks, Clarinda, Iowa, assignor to
 Lisle Corporation, Clarinda, Iowa, a corporation
 of Iowa

Application November 30, 1948, Serial No. 62,710

16 Claims. (Cl. 51—184.2)

1

This invention relates to cylinder hones, and includes a device of that general nature having a hone body and abrasive members that are expandable and contractable and adapted to engage the surface of the cylinder wall.

A serious objection to previous cylinder hones had to do with long and short cylinders. A single cylinder hone was not effective for grinding both long and short cylinders.

If a long hone was used on a short cylinder, the inner ends of the abrasive members became more worn than the portions extending out of the cylinder. Moreover, the hone tended to form a bell mouth on the cylinder; there was no resistance to the expansion of the outer ends of the abrasive members, and as a consequence they were expanded more than the inner ends, forming a taper of the abrasive members which caused the bell mouth of the cylinder.

On the other hand, if a short cylinder hone was used on a long cylinder, the whole surface of the cylinder was not evenly ground, leaving ridges.

An object therefore of the present invention is the elimination of the above objection, and the provision of a cylinder hone which is specially adapted to ready interchangeability of long and short abrasive members.

A more specific object is the provision of a novel construction having a central shaft, a pair of chucks or end members on the shaft, one end member being axially movable with respect to the other, and abrasive members supported solely by the end members.

Another objection to previous types of cylinder hones had to do with blind end cylinders. Ordinary cylinder hones are not effective for grinding the inner end of a blind end cylinder. This is caused by the fact that the abrasive members do not extend fully to the inner end of the hone body, due to improper construction of the hone body. Furthermore, on adjusting the hone for expanding the abrasive members, portions of the hone body extend beyond the inner end of the abrasive members in cases where they would not extend beyond the abrasive members in all positions of adjustment. The present objection applies also in the case of a stepped cylinder having portions of different diameters with a shoulder at the juncture thereof.

Another object therefore of the present invention is the elimination of the above objection, and the provision of a cylinder hone which is specially adapted to grinding blind end cylinders.

A more specific object is the provision of a

2

cylinder hone having a novel construction in which the entering ends of the abrasive members extend into close proximity to the respective end of the hone body.

Still another object of the invention is the provision of a cylinder hone in which the entering ends of the abrasive members extend into close proximity to the respective end of the hone body in all positions of adjustment of the hone.

10 With these and other objects in view, my invention consists in the construction, arrangement and combination of the various parts of my device whereby the objects contemplated are attained as hereinafter more fully set forth, pointed out in the claims and illustrated in the accompanying drawings in which:

Figure 1 is an elevational view of the cylinder hone in expanded position;

20 Figure 2 is similar to Figure 1, showing the hone in retracted position;

Figure 3 is an enlarged longitudinal sectional view of the hone taken on line 3—3 of Figure 5;

Figure 4 is a view similar to Figure 3, showing the hone with short abrasive members therein;

25 Figure 5 is an end view of the device taken from the top of Figure 3;

Figure 6 is a sectional view taken on line 6—6 of Figure 1;

30 Figure 7 is a sectional view taken on line 7—7 of Figure 1;

Figure 8 is a view similar to Figure 7, but showing the cylinder hone in a cylinder with the abrasive members biased toward expanded position and engaging the cylinder wall;

35 Figure 9 is a detail view of one of the abrasive members and taken on line 9—9 of Figure 3;

Figure 10 illustrates the cylinder hone in a short blind end cylinder;

40 Figure 11 illustrates the hone in the large bore of a stepped cylinder; and

Figure 12 is a view showing a portion of a modified form, oriented in accordance with the upper left-hand corner of Figure 4.

45 Referring now in detail to the drawings, the device, as illustrated in Figure 1, includes the hone proper 12 and an adapter 14 secured thereto and provided for connecting the hone with a driving tool. The adapter 14 may be conventional and preferably includes a flexible portion 16 as is usual in such types of adapters.

The hone proper 12 includes a central shaft 18, which for convenience herein, may also be referred to as a body member because of its function of supporting all of the elements of the hone. The shaft 18 extends beyond the hone at one end

55

where it is provided with threads as indicated at 20. The adapter 14 is secured to this threaded portion 20 by means of a set screw 22 or other convenient means. The shaft or body member 18 is polygonal in cross section and, as herein illustrated, is hexagonal.

Mounted on the shaft or body member 18 are a pair of chucks or end members 24 and 26. The end members 24 and 26 are similar to each other in construction. Referring first to the end member 24, this member includes a main body portion 28 in the form of a short axis cylinder and is provided with a central hole 30 for receiving the shaft 18. The hole 30 is of the same cross sectional contour of the shaft so that the end member rotates with the shaft.

An axially extending flange 32 is formed at the periphery of the body member 28 and extends toward the other end member 26. The flange 32 is preferably formed integral with the body member 28 and is formed by cutting away a central cavity.

A plurality of slots 34 are cut in the body member 28 and flange 32. The slots 34 are preferably three in number and extend radially of the end member and terminate inwardly in surfaces 36. The slots 34 are cut entirely through the body member 28 and open axially through both ends of the end member, the slots thus opening radially outwardly and axially of the end member.

A plate 38 is fitted on the end member 24 on the side opposite the flange 32. The plate 38 is provided with a peripheral bead 40 over which is turned a flange 42 formed on the body member 28. The flange 42 thus clamps the plate 38 securely on the end member and the plate closes one end of the slots 34. The plate 38 is provided with a central tapered hole for receiving a reduced portion 44 of the shaft 18. The portion 44 is then swaged or peened to secure the plate 38 in position. The end member 24 is thus fixed on the shaft or body member 18, both against axial movement and against rotation.

The end member 26 is similar in most respects to the end member 24, including the body portion 46, flange 48 and slots 50, the latter having radially inner surfaces 52. An end plate 54 is secured in place similarly to the plate 38. The body member 46 is provided with a central hole 56 for receiving the shaft 18 and is of course of the same cross sectional contour. The plate 54 is provided with a central opening but in this case the plate is not fixedly secured to the shaft. Thus the end member 26 is fixed against rotation on the shaft, but is free to move axially thereon.

A compression spring 58 surrounds the threaded portion 20 of the shaft and is received in a hollow portion 60 of a nut 62 threaded on the threaded portion 20.

The notches 34 and 50, it will be seen from the above, are spaced circumferentially around the end members. The notches are also in axial alignment for the reception of abrasive members indicated generally at 64. Each abrasive member 64 includes an elongated channel member 66 which may be rectangular in cross section having a bottom wall 68 (Figures 5 to 8) and side walls 70. Secured in the channel 66 is an abrasive stone 72. The stone may be rigidly secured in place by clamping the side wall 70 thereon.

Substantially centrally of the abrasive member 64 are a pair of lugs 74 which may be struck out from the bottom wall 68 as indicated in Figure 6. These lugs extend perpendicular to the bottom wall 68 and then inwardly toward each other.

A leaf spring 76 is secured to the channel member by means of the lugs 74. The leaf spring 76 preferably is provided with notches cut in from its lateral edges to receive the lugs 74 to prevent longitudinal displacement of the spring or channel. The lugs 74 are then clamped in place over the leaf spring. The channel 66 and spring 76 are thus connected to each other at a point substantially centrally of each. The ends 78 of the leaf spring 76 are normally biased away from the channel or abrasive member.

Additional lugs 80 are struck out of the channel member 66. These lugs 80 are arranged in pairs and are disposed adjacent the ends of the abrasive member. The lugs 80 are struck out from the side walls 70 and bent down so as to be positioned substantially in the plane of the bottom wall 68 and form lateral projections on the channel 66.

The abrasive members 64 are inserted in the aligned slots 34 and 50 as best illustrated in Figure 3. The end member 26 is axially adjustable on the shaft or body member 18 by means of the nut 62. The end member 26 is retracted away from the end member 24 so that the flanges 32 and 48 are spaced at least as far apart as the opposite outside edges of the lugs 80. The abrasive members 64 are then inserted into the aligned slots so that the ends 78 of the leaf springs rest on the surfaces 36 and 52 of the slots. The abrasive members can then be gripped in one hand and compressed radially inwardly and then the end member 26 is adjusted toward the other end member by turning the nut 62. The end member 26 is run up toward the other end member to the position wherein the flanges 32 and 48 overlie the lugs 80. The abrasive members 64 are then prevented from falling out of the slots or being withdrawn therefrom.

In operation the end member 26 can be retracted from the opposite end member to a position similar to that shown in Figure 2 wherein the abrasive members either retract radially inwardly by themselves or can be retracted by applying pressure by the hand. The hone can then be inserted easily into a cylinder and after the insertion of the hone the end member 26 is adjusted toward the other end member. The ends 78 of the leaf springs are then engaged by the plates 38 and 54 which bows the leaf springs and biases them radially outwardly, forcing the abrasive members radially outwardly into engagement with the surface of the cylinder wall.

The upper end of the hone as seen in Figures 1 to 4 will be referred to as the entering end, that is, the end which enters the cylinder. The thickness of the plate 38 is minor and as a consequence the ends of the abrasive members are in close proximity to the upper surface of the hone. In the case of blind end cylinders such as illustrated in Figure 10 the abrasive members engage the surface of the cylinder wall to a point closely adjacent the closed or blind end of the cylinder.

One of the principal advantages of the present invention resides in that feature wherein different length abrasive members can be inserted at will. In grinding blind end cylinders, or the large diameter of stepped cylinders, it is desirable that the abrasive members be no longer than the length of the cylinder being operated on. If the abrasive members are longer than the cylinder the cylinder may be ground properly, but the outer ends of the abrasive members which extend out of the cylinder are not worn down, leaving a ridge between the outer and inner portions. The

abrasive members must then be dressed so that they are uniform on their abrading surfaces. All previously known cylinder hones are objectionable in that they are not readily adapted to quick change of different lengths of abrasive members, and hence not as effectively adapted for use with different length cylinders.

In the case of the present invention, various lengths of abrasive members are provided to correspond to the different lengths of cylinders. The abrasive members illustrated in Figure 3 are adapted for efficient operation in the case of a cylinder of the same length, then if a shorter cylinder is to be ground the abrasive members can be removed quickly merely by turning the nut 62 and retracting the end member 26. Then shorter abrasive members, such as illustrated in Figure 4, can be inserted and secured in place as described above. A shorter cylinder can then be honed with the same efficiency and effectiveness as in the case of the abrasive members shown in Figure 3 employed in a longer cylinder.

The abrasive members 66 are given considerable radial movement compared with the axial movement of the end member 26. The axial thrust of the end member 26 is exerted on the ends 78 of the leaf springs and due to the bowing of the leaf spring the abrasive members are thrust radially outwardly a considerable amount relative to the axial movement of the end member 26. This is in contrast with previously known types and devices such as those employing wedges, etc.

Another important advantage of the invention resides in the fact that the abrasive members are supported entirely by the end members 24 and 26. A simple construction is thus effected. Complicated arrangements of mechanical elements heretofore employed are thus eliminated. The device is strong and rugged. In the rotation of the device, the abrasive members are engaged and supported by the sides of the slots 34 and 50. The rotational thrust is thus not taken up by the leaf springs, the latter being employed solely for biasing the abrasive members radially outwardly.

I wish to call attention to the fact that the ease of interchangeability of the abrasive members is made possible by the simple construction of the hone. Entire abrasive members can be removed bodily and replaced by others by a simple adjustment of the hone. This is in contrast with other types of hones wherein a fixed arrangement is provided and abrasive carriers, such as the channels 66 must be of fixed length. In the present case the length of the hone is determined by the spacing of the end members and the abrasive members are of the same length as such spacing and are carried by the end members. There is no additional construction required for supporting the abrasive members.

Figure 11 shows a stepped cylinder 84 having a small diameter portion 86 and a large diameter portion 88 with a shoulder 90 therebetween. In effect and for purposes of grinding, the large portion 88 is a blind end cylinder. The hone as illustrated in Figure 11 engages the shoulder 90 and it is desired to grind the surface of the large portion 88 to a point as close as possible to the shoulder 90. The device of the present invention accomplishes this purpose effectively.

Figure 12 illustrates a modified form in which the plate 33 is provided with slots 92 in register with the slots 34, which extend radially in-

wardly a portion of the depth of the slots 34. With this arrangement the ends of the abrasive members can extend through the slots 92 in the end plate while the radially inner portion of the slots 34 are covered to provide thrust surfaces 94 for the ends of the leaf spring. In this way the ends of the abrasive members at the entering end of the hone can be made to extend fully and entirely to the end of the whole device. However, in the construction previously described it has been found that for all practical purposes the ends of the abrasive members terminate sufficiently close to the entering end of the hone.

While I have herein shown and described certain preferred embodiments of my invention, manifestly they are susceptible of modification and rearrangement of the parts without departure from the spirit and scope thereof. I do not therefore wish to be understood as limiting my invention to the precise forms herein disclosed, except as I may be so limited by the appended claims.

I claim:

1. A grinding tool, comprising, in combination, a body member, a pair of axially spaced end members mounted on said body member, each end member having a radially extending body portion and an axially extending peripheral flange, the flanges on said end members being directed toward each other, said end members having axially aligned, circumferentially spaced slots therein, said slots being cut through said flanges and extending radially into said body portions, and abrasive members mounted in respectively aligned slots, each abrasive member including a stone and being mounted on a leaf spring, the ends of the leaf spring engaging the radially inner ends of the slots, the leaf spring thereby biasing the stone radially outwardly, said abrasive members having lateral projections adjacent their radially inner portions in position for engaging the portions of said flanges defining the slots therein for limiting the radially outward movement of said abrasive members.

2. A grinding tool comprising a stem, a pair of axially spaced end members mounted on said stem, flanges on each end member extending toward the other end member, each end member having a plurality of circumferentially spaced slots extending radially therein, the slots of said pair of end members being aligned, abrasive members positioned in pairs of aligned slots, each abrasive member being in engagement with a leaf spring, the ends of said leaf spring engaging the inner radial ends of the slots, thereby biasing the abrasive member radially outwardly, and lateral projections adjacent the radial inner portion of the abrasive members, said lateral projections being located between said end members and adapted to engage the radial inner surface of said flanges, whereby the radial outward movement of said abrasive members is limited.

3. A grinding tool comprising a stem, a pair of axially spaced end members mounted on said stem, flanges on each end member extending toward the other end member, each end member having a plurality of circumferentially spaced slots extending radially therein, the slots of said pair of end members being aligned, abrasive members positioned with their respective ends in aligned slots, resilient bowed leaf springs engaging said abrasive members and biasing said abrasive members radially outward from said slots, lateral projections intermediate the ends of

said abrasive members and adjacent the radial inner portion of the abrasive members, said lateral projections being located between said end members and adapted to engage the radial inner surface of said flanges, whereby the radial outward movement of said abrasive members is limited, and means on said stem operatively associated with at least one of said end members for varying the spacing between said end members.

4. A grinding tool comprising a stem, a pair of axially spaced end members mounted on said stem, one of said end members being slidable on said stem, flanges on each end member extending toward the other end member, each end member having a plurality of circumferentially spaced slots extending radially therein, the slots of said pair of end members being aligned, abrasive members positioned with their respective ends in aligned slots, each abrasive member being in engagement with a leaf spring, the ends of said leaf spring engaging the inner radial ends of the slots, thereby biasing the abrasive member radially outwardly, lateral projections adjacent the radial inner portion of the abrasive members, said lateral projections being located between said end members and adapted to engage the radial inner surface of said flanges, whereby the radial outward movement of said abrasive members is limited, and means for varying the spacing between said end members, said last means including the leaf spring for biasing the end members apart, a nut threaded to said stem, and a spring positioned between said nut and said slidable end member.

5. A grinding tool comprising a stem, a pair of axially spaced end members on said stem, flanges on each end member extending toward the other end member, each end member having a plurality of circumferentially spaced slots extending radially therein, the slots of said pair of end members being aligned, abrasive members positioned with their respective ends in aligned slots, each abrasive member being in engagement with a leaf spring, the ends of said leaf spring engaging the inner radial ends of the slots, thereby biasing the abrasive member radially outwardly, lateral projections adjacent the radial inner portion of the abrasive members, said lateral projections being located between said end members and adapted to engage the radial inner surface of said flanges, whereby the radial outward movement of said abrasive members is limited, outer end plates extending across the outer open ends of the slots and adapted to engage the axial ends of the springs, and means on said stem operatively associated with at least one of said end members for varying the spacing between said end members, whereby the force with which the abrasive members are thrust radially outwardly is varied.

6. A grinding tool comprising a stem, a pair of axially spaced end members on said stem, flanges on each end member extending toward the other end member, each end member having a plurality of circumferentially spaced slots extending radially therein, the slots of said pair of end members being aligned, abrasive members positioned with their respective ends in aligned slots, each abrasive member being in engagement with a leaf spring, the ends of said leaf spring engaging the inner radial ends of the slots, thereby biasing the abrasive member radially outwardly, lateral projections adjacent the radial inner portion of the abrasive members, said lat-

eral projections being located between said end members and adapted to engage the radial inner surface of said flanges, whereby the radial outward movement of said abrasive members is limited, outer end plates extending across the outer open axial ends of the slots and adapted to engage the ends of the springs, means on said stem operatively associated with at least one of said end members for varying the spacing between said end members, whereby the force with which the abrasive members are thrust radially outwardly is varied, and the projected length of said springs being longer than the respective abrasive members, the ends of said springs engaging said outer end plates, and the ends of said abrasive members being spaced from said outer end plates, whereby there is no binding therebetween.

7. A grinding tool comprising a stem, a pair of axially spaced end members on said stem, flanges on each end member extending toward the other end member, each end member having a plurality of circumferentially spaced slots extending radially therein, the slots of said pair of end members being aligned, abrasive members positioned with their respective ends in aligned slots, each abrasive member being mounted on a leaf spring, the ends of said leaf spring engaging the inner radial ends of the slots, thereby biasing the abrasive member radially outwardly, lateral projections adjacent the radial inner portion of the abrasive members, said lateral projections being located between said end members and adapted to engage the radial inner surface of said flanges, whereby the radial outward movement of said abrasive members is limited, and outer end lips extending across the outer open axial ends of the slots adjacent the radially inner ends of said slots, said outer end lips adapted to engage the axial ends of the springs, said lips being small enough to leave the greater portion of the slots unobstructed.

8. A grinding tool comprising a stem, a pair of axially spaced end members on said stem, flanges on each end member extending toward the other end member, each end member having a plurality of circumferentially spaced slots extending radially therein, the slots of said pair of end members being aligned, abrasive members positioned with their respective ends in aligned slots, each abrasive member being mounted on a leaf spring, the ends of said leaf spring engaging the inner radial ends of the slots, thereby biasing the abrasive member radially outwardly, lateral projections adjacent the radial inner portion of the abrasive members, said lateral projections being located between said end members and adapted to engage the radial inner surface of said flanges, whereby the radial outward movement of said abrasive members is limited, outer end lips extending across the outer open axial ends of the slots adjacent the radially inner ends of said slots, said outer end lips adapted to engage the axial ends of the springs, said lips being small enough to leave the greater portion of the slots unobstructed, and said abrasive members extending axially outwardly of said outer end lips.

9. A grinding tool comprising a stem, a pair of axially spaced end members on said stem, the first of said pair of end members being fixed on one end of said stem, flanges on each end member extending toward the other end member, each end member having a plurality of circumferentially spaced slots extending radially therein, the slots of said pair of end members being aligned,

abrasive members positioned with their respective ends in aligned slots, each abrasive member being mounted on a leaf spring, the ends of said leaf spring engaging the inner radial ends of the slots, thereby biasing the abrasive member radially outwardly, lateral projections adjacent the radial inner portion of the abrasive members, said lateral projections being located between said end members and adapted to engage the radial inner surface of said flanges, whereby the radial outward movement of said abrasive members is limited, outer end lips extending across the outer open axial ends of the slots adjacent the radially inner ends of said slots, said outer end lips adapted to engage the axial ends of the springs, the outer end lips on said first end member being small enough to leave the greater portion of the slots unobstructed, and said abrasive members extending axially outwardly of said outer end lips on said first end member.

10. A grinding tool comprising a stem, a pair of axially spaced end members on said stem, each end member having a plurality of circumferentially spaced slots extending radially therein, the slots of said pair of end members being aligned, abrasive members positioned with their respective ends in aligned slots, each abrasive member being in engagement with a leaf spring, the ends of said leaf springs engaging the inner radial ends of the slots, outer end plates extending across the outer open ends of the slots and adapted to engage the ends of the springs, means on said stem operatively associated with at least one of said end members for varying the spacing between said end members, whereby the force with which the abrasive members are thrust radially outwardly is also varied, the projected length of said springs being longer than the respective abrasive members, the ends of said springs engaging said outer end plates, and the ends of said abrasive members being spaced from said outer end plates, whereby there is no binding therebetween.

11. A grinding tool comprising a stem, a pair of axially spaced end members on said stem, the first of said pair of end members being fixed on one end of said stem, each end member having a plurality of circumferentially spaced slots extending radially therein, the slots of said pair of end members being aligned, abrasive members positioned in pairs of aligned slots, each abrasive member being mounted on a leaf spring, the ends of said leaf springs engaging the inner radial ends of the slots, outer end lips extending across the outer open axial ends of the slots adjacent the radially inner ends of said slots, said outer end lips adapted to engage the axial ends of the springs, means on said stem operatively associated with at least one of said end members for varying the spacing between said end members, whereby the force with which the abrasive members are thrust radially outwardly is varied, the lips on said first end member being small enough to leave the greater portion of the slots unobstructed, and said abrasive members extending axially outwardly of said outer end lips on said first end member.

12. A grinding tool comprising a stem, a pair of axially spaced end members on said stem, at least one of said end members being movable axially along said stem toward and away from the other end member to accommodate a plurality of abrasive members of varying lengths, said end members being non-rotatable with respect to said

stem, each end member having a plurality of circumferentially spaced slots extending radially therein, the slots of said pair of end members being aligned, abrasive members, positioned in pairs of aligned slots, said abrasive members being of substantially uniform cross-section along their entire length, resilient means biasing said abrasive members radially outward from said slots, means including elements on said abrasive members and elements on said end members cooperating with each other to limit the radially outward movement of said abrasive members with respect to said end members, elements extending from said abrasive members engageable with said end members for limiting axial movement of said abrasive members with respect to said end members, and said abrasive members extending through the entire axial length of the slots in at least one of said end members and extending axially outward of said one end member, whereby said grinding tool is adapted to be applied to surfaces spaced axially outward of said one end member when said tool is in its operative environment.

13. A grinding tool comprising a stem, a pair of axially spaced end members on said stem, said end members being non-rotatable with respect to said stem, each end member having a plurality of circumferentially spaced slots extending radially therein, the slots of said pair of end members being aligned, abrasive members positioned in pairs of aligned slots, leaf springs in engagement with each abrasive member for resiliently biasing said abrasive members radially outwardly, outer end lips extending across the outer open axial ends of the end member slots adjacent the radially inner ends of said slots, the axial ends of said leaf springs engaging said outer end lips, at least one of said end members being movable axially along said stem toward and away from the other end member to accommodate a plurality of abrasive members of varying lengths, means including elements on said abrasive members and elements on said end members cooperating with each other to limit the radially outward movement of said abrasive members with respect to said end members, elements extending from said abrasive members engageable with said end members for limiting axial movement of said abrasive members with respect to said end members, and said abrasive members extending through the entire axial length of said slots in at least one of said end members and outwardly of the lips on said one end member.

14. A grinding tool comprising a stem, a pair of axially spaced end members on said stem, said end members being non-rotatable with respect to said stem, each end member having a plurality of circumferentially spaced slots extending radially therein, the slots of said pair of end members being aligned, abrasive members positioned in pairs of aligned slots, leaf springs in engagement with each abrasive member for resiliently biasing said abrasive members radially outwardly, outer end lips extending across the outer open axial ends of the end member slots adjacent the radially inner ends of said slots, the axial ends of said leaf springs engaging said outer end lips, at least one of said end members being movable axially along said stem toward and away from the other end member to accommodate a plurality of abrasive members of varying lengths, flanges on each end member extending toward the other member lateral projections adjacent the radial inner portion of the abrasive members and lo-

cated between said end members, said projections adapted to engage the radial inner surface of said flanges, whereby the radial outward movement of said abrasive members is limited, and said abrasive members extending through the entire axial length of said slots in at least one of said end members and outwardly of the lips on said one end member.

15. A grinding tool comprising a stem, a pair of axially spaced end members on said stem, said end members being non-rotatable with respect to said stem, each end member having a plurality of circumferentially spaced slots extending radially therein, the slots of said pair of end members being aligned, abrasive members positioned in pairs of aligned slots, leaf springs in engagement with each abrasive member for resiliently biasing said abrasive members radially outwardly, outer end lips extending across the outer open axial ends of the end member slots adjacent the radially inner ends of said slots, the axial ends of said leaf springs engaging said outer end lips, at least one of said end members being movable axially along said stem toward and away from the other end member to accommodate a plurality of abrasive members of varying lengths, lateral projections adjacent the radial inner portion of the abrasive members and located between said end members, said lateral projections adapted to engage the axial inner surface of said end members, whereby axial movement of said abrasive members with respect to said end members is limited, and said abrasive members extending through the entire axial length of said slots in at least one of said end members and outwardly of the lips on said one end member.

16. A grinding tool comprising a stem, a pair of axially spaced end members mounted on said stem, each end member having a plurality of circumferentially spaced slots extending radially therein, the slots of said pair of end members being aligned, abrasive members positioned in pairs of aligned slots, resilient means biasing said

abrasive members radially outward of said slots, means including elements on said abrasive members and elements on said end members cooperating to limit the radially outward movement of said abrasive members, at least one of said end members being slidably mounted on said stem and movable axially along said stem toward and away from the other end member, resilient means applying forces to opposite sides of said one end member in opposite axial directions, the reaction forces of said resilient means being transmitted to said stem, and means restricting rotation of said end members relative to each other, said means comprising a portion of said stem having a polygonal cross-section, and said end members having apertures of polygonal cross-section adapted to receive therethrough said polygonal portion of the stem.
